UNITED STATES PATENT OFFICE.

HENRY D'OLIER, JR., OF PHILADELPHIA, PENNSYLVANIA.

LAMP-SHADE ATTACHMENT.

SPECIFICATION forming part of Letters Patent No. 783,744, dated February 28, 1905.

Application filed May 10, 1904. Serial No. 207,212.

To all whom it may concern:

Be it known that I, HENRY D'OLIER, Jr., a citizen of the United States, residing at Philadelphia, in the county of Philadelphia and 5 State of Pennsylvania, have invented a new and useful Lamp-Shade Attachment, of which the following is a specification.

My invention relates to means for attaching or applying a reflector or shade to a lamp or 10 lamp-fixture, more especially to an incandescent-lamp socket.

My invention consists of a lamp-fixture shell or casing in which the attachment portion of the shade or reflector engages in a manner 15 to permit the rotation of the shade or reflector with respect to the shell or casing.

It is the object of my invention to provide a shade and attachment which will permit the rotation of the reflector or shade about the 20 lamp, so as to direct the light to any desired region, more especially in the case of an incandescent electric lamp mounted with its axis approximately horizontal, though it should be understood that the herein-described shade attachment may be employed in any other relation.

Reference is to be had to the accompanying drawings, in which—

Figure 1 is a side view, partly in section and 30 partly in elevation, illustrating my invention. Fig. 2 is an end elevational view of the reflector. Fig. 3 is a side elevational view of the reflector.

Referring to Fig. 1, L represents an ordinary incandescent lamp having filament a, the axis of the lamp being approximately horizontal in order that the maximum illumination may be obtained in a vertical direction. The lamp as shown has an Edison base, the screw- 35 threads engaging in the screw-threaded shell member b of the socket, while the central button-contact engages with the contact f of the socket. This lamp-socket is mounted upon a porcelain member inclosed within a casing composed of the two portions C and D, pref- 40 erably of sheet metal.

P is an attachment-plug whose button-contact is represented at d and whose screw-threaded shell-contact is represented at g. Ex- 45 tending axially through the attachment-plug

P is the screw s, whose head contacts with and rotates in the button-contact d. The screw s is rigidly secured to the porcelain member within the casing formed by the members C and D.

55

i is a piece of insulating material in which the screw s engages. Secured to this piece i is the shell member D, held by the screw c. The porcelain member within the casing rotates with respect to the attachment-plug P, 60 and means are provided for maintaining electrical communication between the contacts of the attachment-plug and the lamp-socket contacts B and f in a manner and for a purpose similar to that disclosed in my application filed 65 March 4, 1904, and bearing Serial No. 196,583.

e is a bushing of insulating material immediately surrounding the lamp-socket contact b.

The members C and D have cylindrical portions H, a half being on each member. Each 70 of these cylindrical portions has a bead B, the beads on the two members C and D registering with each other to form a continuous bead or channel within the cylindrical portions.

R represents a shade or reflector, prefer- 75 ably struck out of sheet metal and having its edge curled at I to stiffen it. This reflector corresponds in shape with the outline of the lamp-globe and terminates at its smaller end in a ring member G of the same piece with 80 the body portion of the reflector. This ring portion G is complete except for the gap F.

E is a bead extending around the ring mem- 85 ber G and is of such dimensions as to engage within the bead B on the socket-casing mem- ber, the ring portion G registering within the cylindrical portion H of the casing mem- ber. The gap F renders the ring member G in the nature of a resilient ring which may then expand to snugly engage within the 90 cylindrical portion H. By this means the reflector member R is supported by the casing member and is rotatable about the lamp L, because the ring member G is rotatable within the cylindrical portion H.

95

The ring portion G is placed in proper po- 100 sition within one half of the cylindrical por- tion H—that portion on C, for example. Then the member D is brought into proper relation with respect to C, the cylindrical portion H

on member D then closing around the remaining portion of the ring member G, or with the gap F sufficiently great the ring member G may be compressed by the hand to smaller 5 diameter until the bead E is able to pass into the cylindrical portion H, the members C and D being secured together in normal position. Then the ring member G will expand and fill out the cylindrical portion H, when the bead 10 E will register with the bead B.

As a counterweight corresponding with the counterweight of my aforementioned application the member W is employed, said member having a ring portion with a bead 15 similar to G and E and engaging in the bead B in a cylindrical portion H on the left of Fig. 1.

The member W serves as a pedestal whereby the lamp may stand upon end and be moved 20 about from place to place as a portable lamp.

Though I have shown the ring member G as integral with the body portion R of the reflector or shade member, it is to be understood that such ring member may be made 25 independently of the body portion R and secured thereto by riveting, soldering, or the like.

What I claim is—

1. In combination, a shade comprising a 30 body portion and a ring member, a socket-casing comprising a plurality of members secured together, each of said members engaging said ring member.

2. In combination, a shade comprising a 35 body portion and an incomplete ring member, a socket-casing comprising a plurality of members secured together, and means on said members for engaging said incomplete ring member.

40 3. In combination, a shade comprising a body portion and a beaded ring member, and a socket-casing comprising a plurality of members secured together, said members engaging said beaded ring member.

45 4. In combination, a shade comprising a body portion and a resilient ring member, a socket-casing, and means thereon for embracing said ring member, whereby said shade may rotate with respect to said socket-casing.

50 5. In combination, a shade comprising a body portion and a beaded incomplete ring member, a socket-casing comprising a plurality of members secured together, and a beaded portion on each member, said beaded 55 portions embracing said beaded ring member, whereby said shade may rotate with respect to said socket-casing.

60 6. In combination, a shade comprising a body portion and a ring member secured thereto, a bead on said ring member, a socket-casing, a bead on said socket-casing, said beads registering with each other, whereby said shade may rotate with respect to said socket-casing.

65 7. In combination, a shade comprising a

body portion and a resilient ring member, a bead on said ring member, a socket-casing enclosing said ring member, and a bead on said socket-casing, said beads registering with each other, whereby said shade may rotate with respect to said socket-casing. 70

8. In combination, a shade comprising a body portion and a resilient ring member, and a socket-casing comprising a plurality of members, said ring member being engaged by said 75 members and rotatable with respect thereto.

9. In combination, a shade comprising a body portion and an incomplete ring member, a bead on said ring member, a socket-casing, a bead on said socket-casing, said beads registering with each other, whereby said shade is supported by and may rotate with respect to 80 said socket-casing.

10. In combination, a lamp-socket, a casing therefor, a shade, and a member on said shade 85 engaging inside of said casing.

11. In combination, a lamp-socket, a casing therefor, a shade, and an incomplete ring member on said shade engaging inside of said casing. 90

12. In combination, a lamp-socket, a casing therefor, a shade, and a beaded ring member on said shade engaging inside of said casing.

13. In combination, a lamp-socket, a casing therefor, a shade, and an incomplete ring member integral with said shade and engaging inside of said casing. 95

14. In combination, a lamp-socket, a casing therefor, a shade, and a beaded nearly complete ring member integral with said shade and engaging inside of said casing. 100

15. In combination, a lamp-socket, a casing therefor, a shade, and a member engaging within the opening in said casing for supporting said shade. 105

16. In combination, a lamp-socket, a casing therefor, a shade, and means engaging within the opening in said casing for supporting and permitting the rotation of said shade.

17. In combination, a circuit-terminal-carrying member, a lamp-socket supported thereby and rotatable with respect thereto, a casing for said socket, a shade, and means engaging within the opening of said casing for supporting said shade and permitting its rotation with respect to said casing. 110

18. In combination, a circuit-terminal-carrying member, a lamp-socket rotatable with respect to said member and having its axis at approximately right angles with the axis of said member, a casing for said socket, a shade, and means for engaging in the opening in said casing for supporting and permitting the rotation of said shade. 115

19. In combination, a circuit-terminal-carrying member, a lamp-socket secured thereto and rotatable with respect thereto, and a pedestal secured to said socket. 120

20. In combination, a circuit-terminal-carrying member, a lamp-socket secured thereto 125

and rotatable with respect thereto, the axis of said lamp-socket being approximately at right angles with the axis of said terminal-carrying member, and a weight secured to said socket and serving as a pedestal.

21. In combination, a circuit-terminal-carrying member, a lamp-socket secured thereto and rotatable with respect thereto, a casing for said socket, a shade secured to said casing operating with said casing.

22. In combination, a circuit-terminal-car-

rying member, a lamp-socket secured thereto and rotatable with respect thereto, a casing for said socket, a shade secured to said casing and rotatable with respect thereto, and a detachable pedestal secured to said casing. 15

In testimony whereof I have affixed my hand in the presence of two subscribing witnesses.
